UNITED STATES PATENT OFFICE.

ROBERT S. DRUMMOND, OF DETROIT, MICHIGAN, ASSIGNOR TO DETROIT STEEL PRODUCTS COMPANY, OF DETROIT, MICHIGAN, A CORPORATION OF MICHIGAN.

EXPANSION-JOINT FOR METALLIC WINDOW-SASHES.

1,092,476.

Specification of Letters Patent.

Patented Apr. 7, 1914.

Application filed April 24, 1913. Serial No. 763,355.

To all whom it may concern:

Be it known that I, ROBERT S. DRUMMOND, a citizen of the United States of America, residing at Detroit, in the county 5 of Wayne and State of Michigan, have invented certain new and useful Improvements in Expansion-Joints for Metallic Window-Sashes, of which the following is a specification, reference being had therein 10 to the accompanying drawings.

The invention relates to metallic window construction and has for its object the obtaining of a construction by which the window sash is securely fastened, with a weather 15 proof joint permitting of expansion and contraction.

To this end the invention comprises the construction as hereinafter set forth.

In the drawings: Figure 1 is an elevation 20 of the window sash as applied to a window in a brick wall. Fig. 2 is a vertical cross section thereof. Fig. 3 is a horizontal section. Figs. 4 and 5 are views similar to Fig. 3, showing modifications.

25 A is a metallic window sash of any suitable construction, which is arranged in a window opening such as B in the wall C of the building. To provide for expansion and contraction in the metallic sash, and 30 particularly to provide for such expansion in case of fire, the mounting for the sash is constructed as follows: D is an outwardly-extending flange on the side rail of the sash which is adapted to bear against a ledge or 35 shoulder E formed on the side wall of the window opening. F is a metallic bar, preferably an angle bar, which is also secured to the side wall by suitable means, such as the expansion bolts G anchored in apertures in 40 said wall. The bar F is positioned to bear against the flange D and hold the same in contact with the shoulder E. This flange D does not, however, fill the entire space 45 between the bar F and the shoulder E, as the width of the sash is less than the width of the window opening, so that the parts normally assume the position shown in Fig. 3. This will produce a weather proof joint, 50 but will not interfere with the expansion of the window frame, which is taken care of by the movement inward of the flange D between the bar F and shoulder E.

In Fig. 4 a modified construction is illustrated, in which the metallic bar F is spaced from the bearing E to receive the entire 55 sash rail, this being shown as of angle section. The inwardly-extending flange D' of this rail is parallel to and bears against the bar F, while the edge D² of the angle flange bears against the shoulder E. 60

Fig. 5 shows another modification similar to Fig. 4, but in which the flange D' is parallel to and bears against the shoulder E, while the edge D² of the angle flange bears against the flange of the bar F. 65

Both of these modified constructions provide for expansion and contraction in a similar manner to the construction shown in Fig. 3.

What I claim as my invention is: 70

1. The combination with a wall of a window having an angle-shaped bearing, of a metallic bar secured to one side of said bearing and having an outwardly-extending flange arranged substantially parallel to the 75 other face of said bearing and spaced therefrom, and a metallic sash arranged within said space and adapted to move laterally therein upon expansion, said bearing, bar and sash forming a weather-proof joint. 80

2. The combination with a wall of a window having an angle-shaped bearing, of a metallic bar secured to one side of said bearing having an outwardly-extending flange arranged substantially parallel to the 85 other face of said bearing and spaced therefrom, and a metallic sash having an outwardly-extending flange on its side rail arranged within said space and substantially parallel to the last-mentioned face of the 90 bearing and engaging the same and said flange on the bar, the flange on the sash being tapered and forming a weather-proof joint with the flange on the bar and the bearing. 95

In testimony whereof I affix my signature in presence of two witnesses.

ROBERT S. DRUMMOND.
